UNITED STATES PATENT OFFICE.

JOHN C. QUINN, OF PORT COSTA, CALIFORNIA.

WATER-PRESSURE SAFETY OIL-FEEDER.

SPECIFICATION forming part of Letters Patent No. 703,824, dated July 1, 1902.

Application filed February 11, 1902. Serial No. 93,626. (No model.)

To all whom it may concern:

Be it known that I, JOHN C. QUINN, a citizen of the United States, residing at Port Costa, in the county of Contra Costa and State of California, have invented certain new and useful Improvements in Water-Pressure Safety Oil-Feeders; and I do hereby declare the following to be a full, clear, and exact description of the same.

10 This invention relates to means for supplying liquid fuel to fire-boxes.

The objects of this invention are to provide for the purpose mentioned and analogous uses a liquid-fuel-supplying device which 15 while being adapted to any conditions in which liquid fuel is employed shall be peculiarly adapted for household use. In carrying out this object it is desirable and necessary that the condition of absolute safety 20 from accidental fires shall be provided for. Provision for safety from accidental fires or from the ignition of the fuel in case of destruction of the residence in which this invention is employed by fire is therefore another important object of this invention. 25 Convenience of operation and reliability and simplicity of construction are all necessary and desirable in devices of this character to be used in households. These also are objects of the present invention. All these objects are accomplished by means of the devices illustrated in the accompanying drawings, in which—

30 Figure 1 is a sectional elevation of the device with its pipes and connections to a stove where the fuel is being used. Fig. 2 is a modification in which a different form of safety provision is employed.

Referring to the accompanying drawings, 35 1 is a receptacle of suitable material, shown for convenience as a barrel. This receptacle is supplied with an inlet-pipe 2 for water, connected with a water-main or other suitable supply. It is also furnished with a draw-off pipe 3, having a stop-cock 4. This pipe 3 may be, as is shown, connected with the sewer for the purpose of conducting away the waste water. The receptacle 1 is also provided with another pipe 5, located near its upper extremity. This last-mentioned pipe 5 is also provided with a stop-cock 6. Within the receptacle 1 and preferably attached to its upper

head or cover is a collapsible receptacle 7, of fabric or other suitable material, adapted to contain fuel-oil. Extending through the receptacle 1 and into the interior of the receptacle 7 is a supply-pipe 8, having a stop-cock or valve 9 and an outlet or oil-feed pipe 10. 55

The receptacle 1, with its described attachments, is preferably buried beneath the ground, though where this is undesirable from any reason it may be inclosed within an outer casing of larger size and the space between it and its casing filled with water, earth, or other incombustible material, as shown in 60 Fig. 2. The pipes 2 and 10 are supplied each with a valve or cock to regulate the flow of fluid therethrough. These valves or stop-cocks are operated by the same handle, so as to provide for the simultaneous turning on 65 and off of the oil and the water. I have shown for this purpose a double valve 11, in which the plug 12 is common to both pipes, having a separate port or passage for each supply-pipe, as is shown in section in Fig. 1. 70 13 is a burner of suitable form which is connected with the oil-supply pipe and enters the fire-box. 75

In operation when the valve 12 is opened the water-pressure in pipe 2 is admitted to 80 the receptacle 1 on the outside of the collapsible oil-receptacle 7, thus putting the pressure of the water-main upon the oil contained therein, forcing it through the open valve 12 to the burner 13. 85

Owing to the collapsible character of the oil-receptacle, its contained oil is forced out as used, and the opening or shutting of the oil-valve shuts off also the pressure of the water. When all the oil has been forced out 90 of its receptacle, the waste-valve 4 and the air-valve 6 are opened, thus permitting the water in the receptacle 1 to flow away as waste. The oil-receptacle can then be filled through the oil-supply pipe, the air-valve 95 being open, and the operation again repeated. The contained air in the receptacle 1 is of course permitted to escape around the oil-receptacle, after which the air-valve is closed during the use of the device. 100

As already suggested, the burial of the device in the earth, though usually the most convenient and desirable arrangement, is not of the essence of the invention, it being only

one means of protection. Any other suitable fire - protecting covering, such as that indicated in Fig. 2, may be used.

It is obvious that various changes in the 5 device herein described will readily suggest themselves to mechanics to adapt it to particular circumstances and conditions of operation without departing from the essential character of the invention. I therefore do 10 not confine myself to the particular form or proportion of parts herein described and shown.

What I claim as new, and desire to secure by Letters Patent, is—

- 15 1. A device for containing and supplying fuel-oil and like materials comprising an outer receptacle and an inner collapsible receptacle for oil, and a water-supply pipe to the interior of the outer receptacle exterior to the inner one, and an oil-discharge pipe from the inner receptacle and a valve common to and controlling both of the pipes.
- 20 2. A device for containing and supplying fuel-oil and like materials comprising an outer receptacle provided with a valved waste-pipe and an inner collapsible receptacle for oil having a valved supply-pipe, and a water-supply pipe to the interior of the outer receptacle, exterior to the inner one, and an oil-discharge pipe from the inner receptacle and a valve common to and controlling the water-supply and oil-discharge pipes.

- 25 3. A device for containing and supplying fuel-oil and like materials comprising an outer receptacle provided with a valve-controlled air-inlet and an inner collapsible receptacle for oil and a water-supply pipe to the interior of the outer receptacle, exterior to the inner one, and an oil-discharge pipe from the inner receptacle and a valve common to and controlling both of the pipes.

- 30 4. A device for containing and supplying fuel-oil and like materials comprising an outer receptacle provided with a valved waste-pipe and a valve-controlled air-inlet, and an inner collapsible receptacle for oil having a valved supply-pipe, and a water-supply pipe to the interior of the outer receptacle, exterior to the inner one, and an oil-discharge pipe from the

inner receptacle and a valve common to and controlling the water-supply and oil-discharge pipes.

5. A device for containing and supplying fuel-oil and like materials comprising an outer receptacle inclosed within an incombustible envelop and an inner collapsible receptacle for oil and a water-supply pipe to the interior of the outer receptacle, exterior to the inner one and an oil-discharge pipe from the inner receptacle and a valve common to and controlling both of said pipes.

6. A device for containing and supplying fuel-oil and like materials comprising an outer receptacle inclosed within an incombustible envelop and provided with a valved waste-pipe and an inner collapsible receptacle for oil having a valved supply-pipe and a water-supply pipe to the interior of the outer receptacle, exterior to the inner one, and an oil-discharge pipe from the inner receptacle and a valve common to and controlling the water-supply and oil-discharge pipes.

7. A device for containing and supplying fuel-oil and like materials comprising an outer receptacle inclosed within an incombustible envelop and provided with valve-controlled air-inlet and an inner collapsible receptacle for oil and a water-supply pipe to the interior of the outer receptacle, exterior to the inner one, and an oil-discharge pipe from the inner receptacle and a valve common to and controlling both of the pipes.

8. A device for containing and supplying fuel-oil and like materials comprising an outer receptacle inclosed within an incombustible envelop and provided with a valved waste-pipe and a valve-controlled air-inlet and an inner collapsible receptacle for oil having a valved supply-pipe, and a water-supply pipe to the interior of the outer receptacle, exterior to the inner one, and an oil-discharge pipe from the inner receptacle and a valve common to and controlling the water-supply and oil-discharge pipes.
